UNITED STATES PATENT OFFICE.

JAMES E. ROBISON, OF DENVER, COLORADO.

AUTOMOBILE DOOR-SUPPORTED CLEAN-UP-KIT-HOLDING CASE.

1,411,377.

Specification of Letters Patent. Patented Apr. 4, 1922.

Application filed August 20, 1921. Serial No. 493,996.

To all whom it may concern:

Be it known that I, JAMES E. ROBISON, a citizen of the United States of America, residing at the city and county of Denver and 5 State of Colorado, have invented a new and useful Automobile Door-Supported Clean-Up-Kit-Holding Case, of which the following is a specification.

My invention relates to an automobile 10 door-supporting clean-up-kit holding case.

And the objects of my invention are:

First. To provide a clean-up holding case that is formed on the inside of one of the doors of automobiles.

15 Second. To provide a clean-up kit that contains a wash bowl and other articles, and that opens to form a horizontal shelf on which the wash bowl rests.

Third. To provide a simple, convenient 20 and practical clean-up kit holding case that is attached to the inside surface of one of the doors of automobiles.

I attain these objects by the mechanism 25 illustrated in the accompanying drawings, in which:

Figure 1 is a perspective view showing a portion of one side of an automobile, the door and a tray hinged thereto, said door and tray being arranged to comprise the improved clean-up kit.

Fig. 2 is a vertical, sectional view through the door and hinged tray.

Fig. 3 is a plan view of the tray as seen when swung to a horizontal position, the 35 door being in horizontal section, and

Fig. 4 is a detail sectional view showing the manner of connecting the basin to the tray in a position of use.

Similar letters of reference refer to similar parts throughout the several views.

My clean-up case comprises a double compartment case, one part of which is formed on the inside surface of the front right hand door of Ford automobiles, and the other 45 part is hinged to the door so as to enclose the door, and each part of the case contains contents of personal use.

Referring to the drawings:

The numeral 1, designates the front right 50 hand door of an automobile, preferably of a Ford automobile. The door of a Ford car consists of a sheet of iron 2, that forms its side, and a top rail 3, and a bottom rail 4, both of which are formed of strips of wood that are covered by the upper and 55 lower edges of the side plate 2.

To the under side of the top rail 3, I secure an angled strip 7, of metal that extends across the width of the door to close to the latch 7^A, of the door, to allow one edge 8, 60 to hang down a short distance from the front edge of the strip 3, and below this angled strip 7, I also secure an angled strip 9, to the door plate 2, that is arranged with one edge 10, projecting upwards towards the 65 depending edge 8, of the angled strip 7, and in the same vertical plane, and it is of the same length, and an end portion 9^A, extends from it up to the strip 3.

The projecting edges 8 and 10, are thus arranged 70 to form a pocket 12, behind them and between them and the door plate 2, and the strip 9 forms the floor of the pocket, and this pocket 12, is adapted to hold a hair brush and comb, also a towel and other articles not shown.

Vertical compartments 13 and 14, are formed adjacent the outer side edge of the door, by strips 16 and 17. The partition strip 17, is placed far enough from the outside edge of the door 1, to receive in the space between it and the side strip 15, a clothes brush 19; and the partition strip 16, is placed far enough from the strip 17, to form a space between them wide enough to 85 receive a blacking brush 20, this strip being bent in semicircular form at each end, as shown.

Between the partition strip 16, and the hinged end 21, of the door, a wide vacant 90 space is left, that receives the bottom side of a wash-basin 22, which is removably attached to a folding part of my double compartment clean-up kit holding case, as will be presently described.

I preferably cover the pocket 12, with a curtain or flap 23, which may be made of any suitable fabric or of leather or rubber cloth, and the upper edge of the curtain is secured along the outside surface of the strip 3, so that it will hang down over the sides of the edges 8 and 10, of the angled strips 7 and 9, and thus normally cover the entrance to the pocket, but it is adapted to be thrown up over the top of the door 105 when the articles in the pocket are to be used. A mirror 18, is secured in any suitable manner to the flap 23, and when the flap is in position to cover the pocket 12, the mirror is in position for use, as will be 110 seen by reference to Fig. 1.

The pocket 12, is preferably made about

six inches wide and it is about twelve inches long, while the wash-basin recess is about nine inches square, as only the cone shaped bottom of the wash-basin fits into it when the 5 case is closed.

All of the above parts of my clean-up case that are fixed to the door form the fixed half part of it, and the other half part is hinged to the bottom of the door to swing upwardly.

10 against its front surface, and when the front part is swung open downwardly it is held in a position at right angles to the vertical plane of the door and forms a shelf or wash bench upon which the wash-basin is placed.

15 My invention contemplates any means of so hinging the outer movable part of my double compartment clean-up kit case to permit it to form a shelf and also to allow it to contain other articles of use besides the 20 wash-basin. I preferably, however, carry out this feature of my invention in the following manner:

The outside part of my case comprises a metal tray-shaped member of the same size 25 as the inside surface of the door that is occupied by the opposite fixed part of the case, and it is hinged at its lower edge 24, by hinges 25, to the lower edge of the door 1, and it comprises a metal shallow box-like 30 member that comprises a bottom plate 26, the sides 27, of which are raised and are deep enough to form a box or tray that will receive and hold the wash-basin 22, that is about three inches deep and that is placed 35 bottom side up and with its rim down against the bottom plate 26, against which it is held by a cleat 28, that confines it between the said cleat, and the bottom 29, of a compartment to be presently mentioned.

40 The bottom portion of the wash-bowl, however, projects above the sides of the hinged compartment of the case and projects loosely into the clear space formed in the door part of the case. A soap box 26^A, is secured to 45 the bottom plate 26, of the hinged tray, and is normally covered by the basin 22.

In order to secure the basin to the tray in position for use, an angle bracket A, is secured to the bottom plate and one of the 50 sides 27, of the tray, and this bracket is formed with a socket B, which is vertically disposed when the tray is swung down in a horizontal position. A casting D, is riveted to one side of the basin, on the under side of 55 the rim thereof, and this casting D is provided with a stud E, which is inserted in the socket B, the lug D having a flat face F, which bears against the outer face of the side 27, of the tray, and acts in conjunction 60 with the stud E, to prevent the basin from sagging out of a horizontal position as will be understood by reference to Fig. 4.

At the inner right hand corner of the swinging tray of the case, I partition off a 65 space 31, by means of a partition strip of

metal, in which a box of blacking 33, and a blacking daubing brush 34, are placed, and along the front edge of this swinging tray is formed a compartment 35, which is adapted to be used for soiled towels and for 70 other uses. An angle plate 36, forms the bottom 29, of this compartment, and a side wall which extends about one half the width of the compartment.

In order to secure the swinging half part 75 of my double compartment cleaning-up kit to its fixed part so that it will stop when opened out, and swing down in a position to form a horizontally positioned shelf, I employ a pair of flexible members such as 80 chains C, one end of each of which is secured to the door part of the case, and the opposite end of each of which is secured to the opposite sides of the hinged swinging part in position to substantially support it 85 at substantially right angles to the vertical position of the door. The outer front corner of the swinging part of the case is formed with a recess 37, in it that allows a sufficient clearance space at this corner to 90 manipulate the latch 7^A, of the door to open or close it.

The swinging part of my case is arranged to be secured in a closed position against the 95 fixed door part by a spring latch 37^A, that is secured to the fixed door part and that extends through a slot 38, that is formed in the edge of the swinging part and beyond it, and the outer end of the spring latch is provided with an upwardly projecting lug 39, 100 that springs above the margin of the slot 38, after the lug passes through it, and consequently the swinging part cannot be swung out from the fixed part until the lug is sprung down so that the slot will pass over 105 it. The swinging part of the case can also be locked by a key lock 40, which is secured to the edge of the swinging part, the plunger of which, when the key is turned in locking direction, moves up against the under side of the spring latch and prevents the latch from being sprung down so that the slot 38, will pass over its lug 39.

The operation of my double compartment clean-up kit is as follows:

Assuming that it is fully equipped with the useful articles mentioned and its two compartments are locked together, then when an operator desires to wash and otherwise clean up, he first opens the automobile 120 door and then unlocks the case and swings the hinged swinging part outward and downward until its weight is supported by the chains C, and its weight will hold it down firmly, and in order to prevent the door from accidentally closing, I hook one end of a clip 41, over the inner edge 27, of the swinging part, and the opposite end of this clip is provided with an end that rests on the threshold of the door, and it is provided with 125 130

a downwardly projecting lug portion that projects down past the threshold and bears on the outside of the body of the automobile.

The operator then releases the wash-basin 5 and secures it right side up to the bracket A, in the manner above described, and he can wash up and has at his convenience all of the articles necessary for him to brush his hair and shoes and clothes, and after he is through 10 with the clean-up kit he secures the wash bowl in its place and closes up and locks the swinging part of the fixed door part.

My invention provides a neat, practical clean-up kit for Ford cars that occupies a 15 space that is not at present utilized, and it is of ample size and depth to contain all of the articles necessary for cleaning up or after repair work on the road or in camp, at the end of a journey, and while I have 20 illustrated and described my invention, I do not wish to be limited to the construction shown and described, as changes may be made in its without departing from the spirit of my invention.

Having described my invention, what I 25 claim as new and desire to secure by Letters Patent is:

1. A double compartment clean-up kit case for the doors of automobiles, comprising a 30 half part portion of said kit case constructed on the inside of said door and the other half part portion hinged to the door portion and arranged to be swung down and held in a position to form a shelf for a wash bowl and 35 other articles.

2. A double compartment clean-up kit case for the doors of automobiles, comprising a half part portion of said kit case constructed on the inside of said door and the other half 40 part portion hinged to the door portion and arranged to be swung down and held in position to form a shelf for a wash bowl and other articles, said door containing part being provided with brushes and other useful 45 clean-up articles.

3. A double compartment clean-up kit case for the doors of automobiles, comprising a half part portion of said kit case constructed on the inside of said door and the 50 other half part portion hinged to the door portion and arranged to be swung down and held in position to form a shelf for a wash bowl and other articles, said door containing part being provided with brushes and other useful 55 clean-up articles, and means for latching and also for locking said hinged swinging part of said clean-up case to its door containing part.

4. A double compartment clean-up kit 60 case for the doors of automobiles, comprising a half part portion of said kit case constructed on the inside of said door and the other half part portion hinged to the door portion and arranged to be swung down and held in position to form a shelf for a wash 65 bowl and other articles, said door part of

a wash bowl and other articles, said door containing part being provided with brushes and other useful clean-up articles, and means for latching and also for locking said hinged swinging part of said clean-up case to its door containing part, said means for supporting said downwardly swinging part of said clean-up kit case in a horizontal plane comprising flexible members 70 secured to the sides of each part. 75

5. A double compartment clean-up kit case for the doors of automobiles, comprising a half part portion of said kit case constructed on the inside of said door and the other half part portion hinged to the door 80 portions and arranged to be swung down and held in position to form a shelf for a wash bowl and other articles, said door containing part being provided with brushes and other useful clean-up articles, and means for 85 latching and also for locking said hinged swinging part of said clean-up case to its door containing part, said means for supporting said downwardly swinging part of said clean-up case in a horizontal plane comprising flexible members 90 secured to the sides of each part, and said latch comprising a spring latch provided with a projecting lug secured to the door part of said case, and a slot in said swinging part arranged to be 95 forced over said lug.

6. A double compartment clean-up kit case for the doors of automobiles, comprising a half part portion of said kit case constructed on the inside of said door and the 100 other half part portion hinged to the door portion and arranged to be swung down and held in position to form a shelf for a wash bowl and other articles, said door containing part being provided with brushes and other 105 useful clean-up articles, and means for latching and also for locking said hinged swinging part of said clean-up case to its door containing part, said means for supporting said downwardly swinging part of 110 said clean-up kit case in a horizontal plane comprising flexible members secured to the sides of each part, and said latch comprising a spring latch provided with a projecting lug secured to the door part of said case, and a slot in said swinging part arranged to be forced over said lug, said locking means comprising a key lock secured to said swinging part and arranged so that it will engage said spring latch and 115 prevent its being moved to allow the slot in said swinging member to be moved.

7. A double compartment clean-up kit case for the doors of automobiles, comprising a half part portion of said kit case constructed on the inside of said door and the other half part portion hinged to the door 120 portion and arranged to be swung down and held in a position to form a shelf for a wash bowl and other articles, said door part of 125

4
said double compartment being provided with a horizontal and with vertical pockets for brushes and other articles.

8. A double compartment clean-up kit case for the doors of automobiles, comprising a half part portion of said kit case constructed on the inside of said door and the other half part portion hinged to the door portion and arranged to be swung down and held in a position to form a shelf for a wash bowl and other articles, said door part of said double compartment being provided with a horizontal and with vertical pockets for brushes and other articles, said horizontal pocket being provided with a removable curtain arranged to normally close the entrance to said pocket.

9. The combination with an automobile door, of a tray like member hinged at its lower end to the lower end of the inner side of the door; a latch for holding said tray in a vertical position against said door; means for supporting the tray in a horizontal position, said tray and the inner side of the door being provided with different characters of compartments, and means for defining a space between said tray and the adjacent side of the automobile.

10. The combination with an automobile door, of a tray like member hinged at its lower end to the lower end of the inner side of the door, and a latch for normally holding said tray in a vertical position against said door; chains connected to said door and tray for supporting the tray in a horizontal position, said tray and door being provided with compartments, a bracket on one side of

said tray having a socket and a basin normally supported in a position of disuse in said tray and having a stud thereon, adapted to be inserted in said socket, to support said basin in a position of use.

11. The combination with an automobile door, a tray like member hinged at its lower end to the lower end of the inner side of said door, a latch for holding the tray in a vertical position against the door, chains connected to the door and tray for holding the tray in a horizontal position, said door and tray being provided with variously arranged compartments; of a basin in said tray and means for supporting the same therein in a position of disuse, and members in said basin and said tray whereby the basin can be secured to the tray in a position of use, when the tray is in a horizontal position.

12. The combination with an automobile door, having various compartments on its inner side, including a horizontal compartment at the upper end thereof, of a flap for normally concealing said compartment, said flap being provided with a mirror, a tray-like member hinged to the inner side of said door, means for supporting the same in a horizontal position, a basin therein and means for supporting the same in a position of disuse.

In testimony whereof I affix my signature in presence of two witnesses.

JAMES E. ROBISON.
